UNITED STATES PATENT OFFICE.

SILAS SPRINGSTEEN, OF MANITOWOC, WISCONSIN.

DESIGN FOR A CHURCH-PEW.

SPECIFICATION forming part of Design No. 20,151, dated September 9, 1890.

Application filed August 9, 1890. Serial No. 361,582. Term of patent 14 years.

To all whom it may concern:

Be it known that I, SILAS SPRINGSTEEN, a citizen of the United States, residing at Manitowoc, county of Manitowoc, and State of Wisconsin, have invented and produced a new and original Design for a Pew, which is fully set forth in the following specification, reference being had to the accompanying drawing, forming a part thereof.

5 The essential feature of this design is the form of the seat and back, which are curved in a horizontal plane about a single center and are circumflex in vertical planes radial to the center of horizontal curvature, the 10 back being concave forward at the lower part and convex forward at the upper part, and the seat being convex upward at the forward part and concave upward at the rear part, the radius of the horizontal curvature being 15 quite long relatively to the tangential deflec-

20

tion in the length of the seat—that is to say, the length of the seat occupying a small fraction of an entire circle about the center of its horizontal curvature.

I claim—

25 The design for a pew herein shown and described, of which the seat and back are curved in a horizontal plane about a single center and are circumflex in vertical planes radial to the center of horizontal curvature, the 30 back being concave forward at the lower part and convex forward at the upper part, the seat being convex forward at the lower part and concave forward at the upper part, substantially as set forth.

S. SPRINGSTEEN.
